HEAD MOTION FOR LOOMS

Adolphus H. Landry, North Miami, Fla.

Application December 8, 1950, Serial No. 199,861

6 Claims. (Cl. 139—55)

1

This invention relates to head motions for looms and more particularly to a head motion for operating a multiple harness assembly.

It is among the objects of the invention to provide an improved head motion for textile looms which is effective to operate a number of harness structures in predetermined order; which eliminates the necessity for the main shaft provided in existing looms, providing space within the loom for larger warp beams or for other devices; which is mounted on the top of the loom frame where it is readily accessible for inspection, servicing and repair and is driven directly from the crank shaft of the loom; which positively moves the harness structures at all times, preventing harness skips in the woven fabric, and is capable of operating the harness assembly at a speed which will greatly increase the number of picks per minute now obtained with existing looms; which includes an improved clutch assembly for putting the head motion into and out of operation and an improved crank shaft bearing structure; which directly operates the loom take off mechanism; and which is simple and durable in construction, economical to manufacture, and may be installed on an existing loom or incorporated in a new loom, as may be desired.

Other objects and advantages will become apparent from a consideration of the following description and the appended claims in conjunction with the accompanying drawings wherein:

Figure 1 is an end elevational view of a textile loom equipped with head motion mechanism illustrative of the invention;

Figure 2 is a fragmentary cross sectional view on the line 2—2 of Figure 1;

Figure 3 is a fragmentary cross sectional view on an enlarged scale on the line 3—3 of Figure 1;

Figure 4 is a fragmentary cross sectional view on an enlarged scale on the line 4—4 of Figure 1;

Figure 5 is a fragmentary cross sectional view on the line 5—5 of Figure 4;

Figure 6 is a fragmentary cross sectional view on an enlarged scale on the line 6—6 of Figure 1;

Figure 7 is a fragmentary cross sectional view on the line 7—7 of Figure 6;

Figure 8 is an elevational view of a clutch assembly constituting an operative component of the mechanism with the clutch parts shown in a different relative position from that illustrated in Figure 7; and

2

Figure 9 is a cross sectional view on the line 9—9 of Figure 3.

With continued reference to the drawings, the loom has a pair of spaced apart and substantially parallel end frames, one of which is illustrated in the accompanying drawings and generally designated at 10. When the loom is in operative position these frames are substantially vertically disposed and are provided on their lower ends with spaced apart, adjustable shoes 11 and 12 which rest upon the floor or other horizontal loom supporting surface. The loom mechanism is disposed between the two end frames and carried thereby in a manner well known to the art.

As the loom mechanism is old and well known to the art, it has been considered unnecessary to fully illustrate such mechanism for the purposes of the present disclosure, only those parts 20 of the loom mechanism having a bearing on the improved head motion mechanism of the present invention having been illustrated.

In existing looms a main shaft extends between and is journaled at its opposite ends in 25 the end frames near the rear edges of the end frames and at a convenient distance above the loom supporting surface. As this shaft is not needed when the improved head motion mechanism is used, the drawings illustrate the warp beam arbors 13 journaled in bearings 14 disposed adjacent the locations of the main shaft bearings which are no longer necessary and illustrate a warp beam 15 carried on the arbors 13 and disposed substantially within the space 30 between the two end frames of the loom, the warp beam 15 being materially larger than the warp beams which existing looms equipped with main shafts are able to accommodate.

At their front edges the end frames are provided with upwardly extending horns or standards 16 and a breast beam 17 extends between the upper ends of these standards and is secured at its opposite ends to the standards 16 at the upper ends of the latter. At their rear sides the end frames are provided with upwardly extending frame structures 18 and an arch structure 19 extends between and somewhat above the upper ends of the frame structures 18, the arch structure being bent downwardly at its opposite 45 ends and securely connected to the frame structures 18 at the upper ends of the latter. This arch structure includes two spaced apart and substantially parallel bars 20 and 21, the ends of which are secured to brackets, as indicated at 50 22, which are in turn secured to the upper ends 55 of the corresponding frame structures 18.

A crank shaft 23 extends across the space between the end frames 10 and is journaled at its respectively opposite ends in these end frames at the lower ends of and intermediate the width of the frame extensions 18.

A bearing bracket 24 is mounted on the end frame illustrated in the drawings and has there-in an antifriction bearing receiving the crank shaft 23 near the adjacent end of the latter. A gear 25 is mounted on the crank shaft 23 at the outer side of the bracket 24 and a complementary gear 26 has a hub or axle mounted on the bracket 24 and the gear 26 meshes with and is driven by a gear 25.

The bearing bracket 24 is provided with bearing arms 27 and 28 terminating in bearings disposed one above and the other below the gears 25 and 26 and a vertically disposed shaft 29 is journaled near its lower end in the bearings 30 and 31 carried by the arms 27 and 28 respectively.

A two part clutch, generally indicated at 32, and illustrated in detail in Figures 6, 7 and 8, is mounted on the shaft 29 between the bearings 30 and 31. This clutch comprises a first element 33 slidably mounted on the shaft 29 but drivingly connected to the shaft by suitable means, such as the key 34 carried by the clutch element 33 and slideable in an elongated keyway 35 provided in the shaft 29, and a second element 36 rotatably mounted on the shaft immediately below the element 33.

The element 36 is restrained against movement longitudinally of the shaft by a pin 37 extending through a radial aperture in the clutch element 33 and provided at its inner end with a block 38 received in an annular groove in the shaft 29. The block 38 is resiliently held in the groove 39 by a compression spring 40 mounted in a counterbore in the pin receiving aperture and acting between the block 38 and the end of the counterbore remote from the shaft 29 and the pin is provided outside of the clutch element with a knob or head 41 by means of which the pin can be manually pulled outwardly to release the slide block 38 from the groove 39 and free the clutch element 33 for movement longitudinally of the shaft 29.

The clutch elements 33 and 36 are provided in their abutting faces with complementary semi-cylindrical recesses 42 and 43 respectively providing substantially semicylindrical projections or clutch dogs 44 and 45, the arrangement being such that the clutch dog of each clutch element is received in the recess in the complementary clutch element when the clutch dogs are operatively coupled together.

The two clutch dogs 44 and 45 have wear faces of large area extending diametrically of the corresponding clutch elements and disposed substantially in a plane including the longitudinal center line of the shaft 29 so that wear of the clutch over long periods of time is negligible.

The clutch element 33 has at its end remote from the element 36 a portion 46 of reduced diameter having an annular groove 47 therein. A clutch fork 48 is received in the groove 47 at one end and pivotally connected at its other end to the bearing bracket 24, and suitable means are connected to this fork for raising the element 33 away from the element 45 when it is desired to uncouple the clutch and discontinue operation of the head motion mechanism.

A beveled gear formation 50 is formed on the end of the clutch element 36 remote from the

clutch element 33 and meshes with a beveled gear 51 carried by the gear 26 coaxially with the axis of rotation of this gear.

With this arrangement, when the crank shaft 5 of the loom is rotating, and the clutch 32 is coupled, the vertical shaft 29 will be rotationally driven by the crank shaft of the loom.

Bearings 52 and 53 are mounted one on each of the arch bars 20 and 21 near the bracket 22 and a jack shaft 54 is journaled in these bearings and extends transversely of the frame arch and of the crank shaft 23. One end of the jack shaft 54 is disposed adjacent the upper end of the vertical shaft 29 and beveled gears 55 and 56 are mounted on the jack shaft and the vertical shaft respectively and intermesh to provide a driving connection from the vertical shaft to the jack shaft. An angle bracket 57 has bearings disposed one at each end thereof and one receiving the jack shaft 54 adjacent the gear 55 and the other receiving the vertical shaft 29 adjacent the beveled gear 56 to hold the beveled gears 55 and 56 in meshing relationship with each other.

Bearings 58 and 59 are mounted on the arch bars 20 and 21 respectively above the bearings 52 and 53 and a cam shaft 60 is journaled in these bearings 58 and 59. A gear 61 is mounted on the jack shaft 54 at the end of this shaft remote from the beveled gear 55 and a gear 62 is mounted on the corresponding end of the cam shaft 60 and meshes with the gear 61, the gears 61 and 62 providing a driving connection from the jack shaft 54 to the cam shaft 60.

Two arms 63 and 64 are disposed in upright position adjacent the cam shaft 60 and are pivotally mounted at their lower ends by means of corresponding bearing sleeves 65 and 66 on a shaft 67 the opposite ends of which are secured in bracket extensions 68 secured to and projecting from the under side of the arch bars 20 and 21 respectively near the ends of these bars secured to the bracket 22. The sleeve 65 is secured to the arm 63, the sleeve 66 is secured to the arm 64 and the arms are held in properly spaced apart positions relative to each other by a spacer sleeve 69 surrounding the shaft 67 between the arms. Near their upper ends the arms 64 and 65 are provided on their edges facing the cam shaft 60 with a series of notches 70 and 71, for a purpose to be presently described.

Two cylindrical cams 71 and 72 are eccentrically mounted on the cam shaft 60 between the arch bars 20 and 21 and these cams are disposed substantially 180 degrees out of phase with each other. These cams are held in position between the arch bars by spacer sleeves 73 and 74 surrounding the cam shaft 60 and respectively disposed between the arch bar 20 and the cams and the arch bar 21 and the cams. The cams are held in spaced apart relationship by a bearing washer 75 disposed therebetween.

A connecting link 76 has at one end an annular enlargement receiving the cam 71 and an antifriction bearing including antifriction ball elements 77 is disposed between the cam 71 and the end enlargement of the connecting link 76. At its other end the connecting link 76 is provided with a transversely projecting pin 78 received in an aperture in the arm 63 above the shaft 67. A similar connecting link 79 has at one end an annular enlargement receiving the cylindrical cam 72 and an antifriction bearing including the antifriction ball elements 80 is disposed between the periphery of the cam 72 and the enlarged

end formation of the connecting link 13. The connecting link 79 has at its other end a transversely extending pin 81 received in an aperture in the arm 64 above the shaft 67.

With this arrangement, when the cam shaft 60 is rotated, as explained above, the arms 63 and 64 will be rocked or oscillated back and forth about the axis of their pivotal mountings on the shaft 67.

Vertically movable harness structures, generally indicated at 82, are disposed between the end frames of the loom and below the arch 19. These harness structures are of well known construction and are connected to the warp threads to alternately move adjacent warp threads in opposite directions to provide the shed for the loom shuttle in a manner well known to the art.

Sheaves, as indicated at 83 and 84, are disposed between the arch bars 29 and 21 above the harness structures 82 at spaced apart locations along the arch bars and are rotatably mounted on shafts 85 and 86, the ends of which are received in suitable apertures provided in the arch bars. Flexible strands 87 and 88 are connected to one of the harness structures 82 at spaced apart locations along the upper edge of the harness structure and are carried over sheaves 83 and 84 respectively toward the arms 63 and 64. At their ends remote from the corresponding harness structure the strands 87 and 88 are connected to a clip 90 which is hung on the arm 64 and positioned longitudinally of the arm by engaging in a selected one of the notches 70.

Similar strands 91 and 92 are connected to another of the harness structures 82 at one end and connected by a clip 93 to the other arm 63, the clip being engaged in a selected notch 69 to position the clip longitudinally of the corresponding arm.

It is to be understood that each arm may be connected to one or more harness structures so that groups including several harness structures can be moved in respectively opposite directions by the head motion and also that additional arms may be provided and operatively connected to the crank shaft in the above described manner, if desired.

The arms 63 and 64 act to raise the harness structures connected thereto and these harness structures are returned downwardly by suitable tension springs 94 connected between the bottom edges of the harness structures and a frame member 95 extending across the space between the end frames 10 near the lower ends of these frames and secured at its respectively opposite ends to the end frames.

A shaft 96 is substantially horizontally disposed at the outer side of the end frame 10 and has one end positioned adjacent the lower end of the vertical shaft 29. A beveled gear 97 is secured on the lower end of the shaft 29 and a complementary beveled gear 98 is secured on the end of the shaft 96 adjacent the shaft 29 and meshes with the beveled gear 97 to provide a driving connection from the shaft 29 to the shaft 96. An angle bracket 99 is connected at one end to the lower bearing 31 for the shaft 29 and is provided at its other end with a bearing 100 which receives the shaft 96 adjacent the beveled gear 98 to maintain the beveled gears 97 and 98 in proper meshing relationship. Near its other end the shaft 96 is journaled in a bearing 101 secured on the end frame 10 near the front edge of the latter and a worm 102 is mounted on the shaft 96 adjacent the bearing 101 and meshes with a

worm gear 103 which drives the take off beam or roll of the loom. The shaft 96 extends forwardly of the end frame beyond the bearing 101 and is provided on its end remote from the beveled gear 98 with a hand wheel 104 by means of which the take off mechanism can be manually operated, when necessary, to remove slack from the fabric.

The above described construction provides the head motion mechanism entirely on the outside of the loom where it is readily accessible for inspection, servicing and repair and positions the major portion of the head motion mechanism above the loom where it is out of the way. Removing the head motion mechanism from the lower portion of the space between the end frames of the loom makes this space available to receive the warp beam 15 and provides adequate space to accommodate a warp beam of increased size since the main shaft usually provided in the loom is no longer necessary. The direct drive from the loom crank shaft to the head motion mechanism provides a positive operation of the harness structures 82 eliminating the condition known as harness skips and, because of the rigid construction of the head motion mechanism, the rigid mounting of this mechanism on the loom frame and the provision of antifriction bearings where necessary, the speed of operation of the head motion mechanism can be materially increased to substantially increase the operative capacity of the loom.

As is particularly illustrated in Figures 4, 5 and 6, the bearing bracket 24 comprises a flat plate portion 105 of rectangular shape which overlies the outer side of the end frame 10 at the bottom of the space between the two upwardly extending standards of the frame extension 18 and is provided with spaced apart apertures receiving bolts 106 and 107 which extend through spaced apart and horizontally disposed slots in the end frame to adjustably secure the bracket to the end frame. A bearing housing 106' is formed at the upper edge of the rectangular plate portion 105 and extends across the adjacent horizontal edge of the frame to receive the corresponding end of the crank shaft 23. Antifriction roller elements 107' are disposed in the housing 106' surrounding the shaft 23 and the housing is split at its upper side to provide two spaced apart lugs 108 and 109. A filler block 110 is disposed between the lugs 108 and 109 and this filler block and the lug 109 are provided with registering apertures while the lug 108 is provided with a tapped hole registering with the apertures in the filler block in the lug 109. A clamp bolt 111 extends through the apertures in the lug 109 and in the filler block 110 and is threaded into the tapped hole in the lug 108 to secure the antifriction elements 107' in the housing surrounding the shaft 23.

By varying the thickness of the filler block 110 the bearing can be adjusted to compensate any wear therein.

A pin 112 is secured at one end to the plate portion 105 at a location spaced from the bearing housing 106' and constitutes an axle for the gear 26. Antifriction roller elements 113 are disposed in the gear 26 surrounding the axle pin 112 to provide an antifriction bearing mounting for this gear. The bearing arm 28 projects from the plate portion 105 immediately below the pin 112 while the bearing arm 27 projects from the bearing housing 106' for the crank shaft 23.

A collar 114 adjustably secured on the shaft 29 bears against the upper end of the bearing 30 for this shaft to secure the shaft against down-

ward longitudinal movement relative to the bearings 30 and 31 and the beveled gear 97 bears against the lower end of the bearing 31 to hold the shaft 29 against upward movement.

The improved bearing bracket above described greatly increases the rigidity of the head motion mechanism and obviates any slack or lost motion in the operation of the mechanism and the improved, wear-resisting clutch also obviates lost motion or slack in this part of the mechanism so that the movements of the harness structures are always exactly timed to the operation of the loom crank shaft and are positively moved, thus permitting the increase in the speed of the loom, as indicated above.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. In combination with a loom having end frames, an arch disposed above and mounted at its ends on said end frames, a crank shaft journaled in said end frames and disposed below said arch, and a head motion mechanism mounted on said arch at one end thereof and adjacent one of said end frames, means drivingly connecting said crank shaft to said head motion mechanism comprising a bracket mounted on said one end frame at the corresponding end of said crank shaft, a vertically disposed shaft journaled in said bracket and extending between said crank shaft and said head motion mechanism, gear means drivingly connecting said shaft at the end thereof adjacent said head motion mechanism to the latter, a clutch mounted on said shaft and including two separable parts one of which is drivingly connected to said vertically disposed shaft and the other which is rotatably mounted thereon and drivingly connected thereto only when said two clutch parts are together, and gear means drivingly connecting said crank shaft to said other clutch part.

2. In combination with a loom having end frames, an arch disposed above and mounted at its ends on said end frames, a crank shaft journaled in said end frames and disposed below said arch, and a head motion mechanism mounted on said arch at one end thereof and adjacent one of said end frames, means drivingly connecting said crank shaft to said head motion mechanism comprising a bracket mounted on said one end frame at the corresponding end of said crank shaft, a vertically disposed shaft journaled in said bracket and extending between said crank shaft and said head motion mechanism, gear means drivingly connecting said shaft at the end thereof adjacent said head motion mechanism to the latter, a clutch mounted on said shaft and including two separable parts one of which is drivingly connected to said vertically disposed shaft and the other which is rotatably mounted thereon and drivingly connected thereto only when said two clutch parts are together, and gear means drivingly connecting said crank shaft to said other clutch part, said last mentioned gear means comprising a stub shaft mounted on said bracket adjacent said other clutch part, a com-

bination spur gear and beveled gear formation on said other clutch part meshing with the beveled gear component of said combination gear, and a spur gear fixed on said crank shaft and meshing with the spur gear component of said combination gear.

3. In combination with a loom having end frames, an arch disposed above and mounted at its ends on said end frames, a crank shaft journaled in said end frames and disposed below said arch, and a head motion mechanism mounted on said arch at one end thereof and adjacent one of said end frames, means drivingly connecting said crank shaft to said head motion mechanism comprising a bracket mounted on said one end frame at the corresponding end of said crank shaft, a vertically disposed shaft journaled in said bracket and extending between said crank shaft and said head motion mechanism, gear means drivingly connecting said shaft at the end thereof adjacent said head motion mechanism to the latter, a clutch mounted on said shaft and including two separable parts one of which is drivingly connected to said vertically disposed shaft and the other which is rotatably mounted thereon and drivingly connected thereto only when said two clutch parts are together, and gear means drivingly connecting said crank shaft to said other clutch part, the gear means connecting said crank shaft to said vertically disposed shaft and the gear means connecting said vertically disposed shaft to said head motion mechanism each including a pair of intermeshing spur gears.

4. In combination with a loom having end frames, an arch disposed above and mounted at its ends on said end frames, a crank shaft journaled in said end frames and disposed below said arch, and a head motion mechanism mounted on said arch at one end thereof and adjacent one of said end frames, means drivingly connecting said crank shaft to said head motion mechanism comprising a bracket mounted on said one end frame at the corresponding end of said crank shaft, a vertically disposed shaft journaled in said bracket and extending between said crank shaft and said head motion mechanism, gear means drivingly connecting said shaft at the end thereof adjacent said head motion mechanism to the latter, and means drivingly connecting said crank shaft to said vertically disposed shaft comprising a stub shaft mounted on said bracket and projecting outwardly therefrom, a combination beveled gear and spur gear journaled on said stub shaft, a spur gear fixed on said crank shaft and meshing with the spur gear component of said combination gear, a first clutch body having a bore extending therethrough and rotatably receiving said vertically disposed shaft, a beveled gear formation on one end of said first clutch body meshing with the beveled gear component of said combination gear, an extension on the other end of said first clutch body providing a face substantially in a plane including the rotational axis of said vertically disposed shaft, a second clutch body mounted on said vertically disposed shaft adjacent said other end of said first clutch body, an extension on the end of said second clutch body adjacent said first clutch body providing a face substantially in a plane including the rotational axis of said vertically disposed shaft, said extensions overlapping with said faces in mutually opposed engagement when said clutch bodies are together, and means providing a driving connection between said second clutch body

and said vertically disposed shaft while providing freedom of sliding movement of said second clutch body longitudinally of said vertically disposed shaft toward and away from said first clutch body.

5. In combination with a loom having end frames, an arch disposed above and mounted at its ends on said end frames, a crank shaft journalled in said end frames and disposed below said arch, and a head motion mechanism mounted on said arch at one end thereof and adjacent one of said end frames, means drivingly connecting said crank shaft to said head motion mechanism comprising a bracket mounted on said one end frame at the corresponding end of said crank shaft, a vertically disposed shaft journalled in said bracket and extending between said crank shaft and said head motion mechanism, gear means drivingly connecting said shaft at the end thereof adjacent said head motion mechanism to the latter, and means drivingly connecting said crank shaft to said vertically disposed shaft comprising a stub shaft mounted on said bracket and projecting outwardly therefrom, a combination beveled gear and spur gear journalled on said stub shaft, a spur gear fixed on said crank shaft and meshing with the spur gear component of said combination gear, a first clutch body having a bore extending therethrough and rotatably receiving said vertically disposed shaft, a beveled gear formation on one end of said first clutch body meshing with the beveled gear component of said combination gear, an extension on the other end of said first clutch body providing a face substantially in a plane including the rotational axis of said vertically disposed shaft, a second clutch body mounted on said vertically disposed shaft adjacent said other end of said first clutch body, an extension on the end of said second clutch body adjacent said first clutch body providing a face substantially in a plane including the rotational axis of said vertically disposed shaft, said extensions overlapping with said faces in mutually opposed engagement when said clutch bodies are together, means providing a driving connection between said second clutch body and said vertically disposed shaft while providing freedom of sliding movement of said second clutch body longitudinally of said vertically disposed shaft toward and away from said first clutch body, and manually releasable latch means carried by said second clutch body and engaging said shaft to hold said clutch body together.

6. In combination with a loom having end frames, an arch disposed above and mounted at its ends on said end frames, a crank shaft journalled in said end frames and disposed below said arch, and a head motion mechanism mounted on said arch at one end thereof and adjacent one of said end frames, means drivingly connecting said crank shaft to said head motion mechanism comprising a bracket mount-

ed on said one end frame at the corresponding end of said crank shaft, a vertically disposed shaft journalled in said bracket and extending between said crank shaft and said head motion mechanism, gear means drivingly connecting said shaft at the end thereof adjacent said head motion mechanism to the latter, a clutch mounted on said shaft and including two separable parts one of which is drivingly connected to said vertically disposed shaft and the other which is rotatably mounted thereon and drivingly connected thereto only when said two clutch parts are together, and gear means drivingly connecting said crank shaft to said other clutch part, said bracket comprising a plate portion secured to said one end frame and having on one edge a bearing housing formation receiving said crank shaft, said bearing housing formation being split to provide spaced apart apertured lugs at one side thereof, an apertured filler block between said lugs, antifriction elements in said housing surrounding said crank shaft, a clamp bolt extending through said lugs and said filler block to adjust the internal size of said housing, an axle pin secured at one end to said plate portion and projecting outwardly therefrom at a location spaced from said bearing housing, a first bearing arm projecting from said bearing housing, a first bearing on the distal end of said bearing arm, a second bearing arm projecting from said plate portion at a location adjacent said axle pin and in a direction substantially opposite to said first bearing arm, and a second bearing on the distal end of said second bearing arm, said first and second bearings rotatably receiving said vertically disposed shaft and having a common axis disposed at substantially right angles to the axis of said crank shaft, and said gear means drivingly connecting said crank shaft to said vertically disposed shaft including a combination spur gear and beveled gear journalled on said axle pin, a spur gear on said crank shaft meshing with the spur gear component of said combination gear, and a beveled gear drivingly connected to said vertically disposed shaft and meshing with the beveled gear component of said combination gear.
